(57) **CLAIM**

The ornamental design for a pocket pop-up speaker, as shown and described.

DESCRIPTION

FIG. 1 is a perspective view of a pocket pop-up speaker showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is another front elevational view thereof, in pop-up position;

FIG. 8 is another rear elevational view thereof, in pop-up position;

FIG. 9 is another left side elevational view thereof, in pop-up position;

FIG. 10 is another right side elevational view thereof, in pop-up position; and,

FIG. 11 is another perspective view thereof, in pop-up position.

The broken lines shown in the drawings illustrate portions of the article and form no part of the claimed design.
